(CL. D81—10)

To all whom it may concern:

Be it known that we, Theodore D. Nierenberg and George Daelemans, citizens of the United States and residents of Dayton, in the State of Ohio, with post-office address c/o Etched Products Corporation, 39-01 Queens Boulevard, Long Island City, New York, have invented a new, original, and ornamental Design for a Combined Toaster and Hot Plate, of which the following is a specification, reference being had to the accompanying drawing, forming part thereof, in which:

Fig. 1 is a perspective view of the combined toaster and hot plate showing our new design in closed position.

Fig. 2 is a perspective view of the same in open position.

We claim:

The ornamental design for a combined toaster and hot plate, as shown.

THEODORE D. NIERENBERG.
GEORGE DAELEMANS.
